UNITED STATES PATENT OFFICE.

LOUIS MOURAS, OF VESOUL, FRANCE.

CESSPOOL.

SPECIFICATION forming part of Letters Patent No. 268,120, dated November 28, 1882.

Application filed April 5, 1882. (No model.) Patented in France September 22, 1881, No. 144,904; in Russia December 8, 1881; in England December 9, 1881, No. 5,391; in Belgium December 10, 1881, No. 56,454; in Germany December 10, 1881, No. 18,641; in Austria December 13, 1881, No. 41,450; in Italy December 19, 1881, and in Spain December 26, 1881, No. 2,365.

To all whom it may concern:

Be it known that I, LOUIS MOURAS, a citizen of the French Republic, residing at Vesoul, department of Haute-Saone, France, have invented certain Improvements in Cesspools and in Means of Draining the Same, of which the following is a specification.

So far as I am aware, there are but three methods now in use for cleansing and evacuating cesspools. The first is by means of the stationary or fixed drain, which has the great inconvenience of giving place to emanations which are injurious, and this drain demands frequent expenditures, and is very disagreeable to man-
5 age. The second is by means of the movable drain, the management of which is always annoying and disagreeable. The third is by means of a sewer, in which case a large flow of water in the sewer is required for scouring and for
10 carrying away the heavier matters to the river or sewer-outlet.

By my present invention I have sought to avoid all of the inconveniences of the systems above described. My cesspool is hermetically
15 closed, and both the inlet and the outlet pipes are sealed in the liquid contents of the cesspool, which hermetically closes them and prevents the escape of gases.

In the drawings which serve to illustrate
30 my invention, Figure 1 is a vertical section on line 1 1 in Fig. 2, and Fig. 2 is a plan of my invention in its ordinary form. Fig. 3 is a vertical section of the same, but arranged to show the discharge of the matters from the cess-
35 pool into the sewer above the level of the wa-
ter therein. Fig. 4 is also a sectional view, showing the discharge-pipe as entering the sewer below the water-level therein, and also showing a provision on the discharge-pipe to
40 prevent siphoning.

A represents the vault of the cesspool, built with a concrete bottom or bed, D, strong concrete or masonry side walls, E, and a lining, F.

G are the flags, which form the covering of
45 the cesspool and the outlet-passage J. These are laid in cement, and their beveled joints L filled with cement, as shown.

B is the inlet to the cesspool, whereby all

the fecal matter, water, &c., enter; and C is the outlet, which is connected by the passage 50 J with a pipe, P, which leads into a sewer, O.

K indicates in dotted lines in Fig. 1 another route to the sewer.

I is a sealed plug in the cover G, which may be removed and the passage J inspected; and 55 H is a man-hole cover, which also fits hermetically, and at which access may be had to the interior of the vault.

The discharge-pipe C is arranged at or near the top, and the evacuation does not begin 60 until the vault of the cesspool is nearly full. Then when any matter enters by the pipe B a corresponding amount of liquid is discharged at C, the level of the fluid mass in the vault remaining always the same. It is only liquid, 65 however, that is discharged, this liquid holding in suspension and solution the matters arising from the decomposition and disaggregation of fecal and other matters entering the vault. It is advantageous, therefore, to allow 70 all the surface and waste water to pass into the cesspool on its way to the sewer. With this arrangement the removal of the fecal and other matter is constantly going on, and no gas can possibly escape, as the exits are all 75 sealed. When the discharge-pipe dips into the sewer, as shown in Fig. 1, below the low-water level therein the discharged matter becomes thoroughly mixed with the waters in the sewer and is borne away without being 80 exposed even to the air in the sewer.

In order to prevent the collection of hard and insoluble substances in the vault—such, for example, as broken glass or china and gravel, which will fill up the vault in course of time— 85 I provide the means I will now describe.

M is a tray or box with a grated or perforated bottom, which is suspended from the cover G by means of suspending links or rods N N, two at each end. This tray is arranged under 90 the inlet-pipe B, and receives all the solid substances which enter the vault. It is provided with a chain, N', one end of which is attached to the tray and the other to a hook at or near the man-hole in the vault-cover. From time 95 to time the cover H is removed and the tray
